UNITED STATES PATENT OFFICE.

CHARLES S. ASH, OF HAGERSTOWN, MARYLAND.

APPARATUS FOR USE IN CONNECTION WITH APPLYING PAINT.

1,382,882.

Specification of Letters Patent. Patented June 28, 1921.

Application filed August 6, 1919. Serial No. 315,592.

To all whom it may concern:

Be it known that I, CHARLES S. ASH, a citizen of the United States, residing at Hagerstown, in the county of Washington 5 and State of Maryland, have invented certain new and useful Improvements in Apparatus for Use in Connection with Applying Paint, of which the following is a full, clear, and exact description, such as will enable 10 others skilled in the art to which it appertains to make and use the same.

This invention relates to apparatus for use in the application of paint or the like to articles of manufacture. The apparatus 15 herein described is designed particularly for use in connection with spraying paint on wire spoked vehicle wheels.

It is the primary object of the invention to provide an improved construction and assembly of parts whereby the thorough and rapid painting of such wheels may be efficiently and economically carried on.

Other objects and advantages will appear from the following description of the accompanying drawing, which illustrates a preferred embodiment of the invention, and in which,—

Figure 1 is a side elevation of the apparatus;

Fig. 2 is a partial end view thereof, showing a wheel mounted in the painting chamber; and

Fig. 3 is a partial top view of the painting chamber.

Referring more particularly to the drawing, there is shown a horizontally disposed tubular member 1 supported on upright pedestals 2 and having opposite open ends through which a wire spoked vehicle wheel 3 or other article to be treated may be fitted on or removed from a supporting stand 4 therein. The member 1 is of a longitudinal dimension such that it may be divided centrally by a wall, shown in dotted lines at 5 in Fig. 1 and extending from the bottom of the member to a distance within a vertical flue 6 connecting the painting chambers with a flue 7 leading to an air exhauster 8. The division wall 5 separates the member 1 into 10 two end painting chambers, in either of which the painting operation can be carried on separately, or in both of which separate operations can be carried on simultaneously.

The air exhauster 8, such as an exhaust fan, is provided to create by suction a strong current of air entering the open ends of the

painting chambers and transmitted through the flues 6 and 7 to the exit 9. In order to control the degree of suction and to render the painting chambers at the opposite ends 60 of the member 1 independent, sliding dampers 10 and 11 are mounted at the upper interior of the member 1 and operable to open or close communication between the same and the flue 6. 65

In use, a wheel 3 may be mounted in either of the painting chambers and its corresponding damper opened, whereupon, by a spraying device, paint may be thoroughly and rapidly applied to the wheel. This application is facilitated in the present instance by making the supporting standard 4 rotatable, so that the wheel thereon is capable of bodily movement about a vertical axis, as well as spinning about the horizontal axis of its hub. 70 The air current drawn by the exhauster 8 carries away from the operator all the surplus paint spray and fumes. Moreover, on account of the division wall 5, it will be seen that two wheels may be simultaneously 75 painted in the opposite ends of the chamber 1 with paint of different colors without liability of objectionable intermixture of the colors, before the waste surplus has been drawn above the end of the wall 5 which 80 projects into the flue 6, beyond which point their continued separation and recovery is unnecessary. A considerable quantity, however, of the surplus sprayed paint will 85 impinge on the walls of the respective chambers, and for the recovery thereof these chambers are provided with drains 12 and 13 with which pails may be associated to collect the surplausage of unmixed color. 90

The flue 7 is provided with a sliding door 95 14, affording access to the interior of flue 7, whereby the latter may be cleaned at intervals, as necessary. A similar door 15 is preferably arranged at the top of flue 6. By arranging the exhauster 8 at a considerable 100 distance from the painting chambers, as described, it is subjected to a minimum collection thereon of the paint spray, since by far the major portion thereof drops from suspension in the air during its travel through 105 the horizontal flue 7 and prior to reaching the exhauster.

In practice, the flue 7 is preferably extended and a plurality of the chambers 1 connected therewith at intervals along its 110 length, so that the single exhauster 8 and single flue 7 serve, in common, as many of

the painting chambers as the particular installation requires. At the same time this construction also permits a maximum utilization of the available space.

- 5 As shown in Fig. 3, corresponding corners 16 of the painting chamber may be cut obliquely so that the chamber may be mounted parallel to a factory wall or to the lighting source, whereby direct light may conveniently reach the two end painting chambers equally. This construction, as will be understood, also permits the member 1 to be conveniently installed in a corner with the light reaching the same through the two 15 corner walls.

Having described my invention, what I claim as new and desire to secure by Letters Patent is:

1. In apparatus of the character described, 20 in combination, a tubular member having opposite open ends, an interior wall dividing said member into two separate painting chambers, an exhauster spaced from said member, and flues connecting said exhauster 25 and said painting chambers.

2. In apparatus of the character described, 30 in combination, a horizontally mounted tubular member having opposite open ends, an interior wall dividing said member into separate painting chambers, an exhauster, a flue connecting said exhauster and said

painting chambers, and separate dampers for opening or closing communication between said chambers and said flue.

3. In apparatus of the character described, 35 in combination, a tubular member having opposite open ends, an interior wall dividing said member into separate painting chambers, and separate drains from said chambers.

4. In apparatus of the character described, 40 in combination, a horizontally mounted tubular member, an interior wall dividing said member into separate painting chambers, an exhauster removed from said member, a horizontal flue leading to said exhauster, and a vertical flue connecting said first-mentioned flue with said member.

5. In apparatus of the character described, 45 in combination, a horizontally mounted tubular member having opposite open ends, and an interior wall dividing said member into separate painting chambers, the ends of said member at one side being cut away for the purpose described.

In testimony whereof I affix my signature, in the presence of two witnesses.

CHARLES S. ASH.
